4 Claims. (Cl. 24—242)

1

This invention has to do with a well tool comprising a unitized block and hook presenting new features of load distribution. The device is rigidly supported through the use of a common load-carrying frame, from which swinging bail, beackets and couplings have been entirely eliminated. This has been done in the interest of safety, and for the purpose of shortening the device, and also to conserve operating space and to afford more efficient use of the short gin pole or A frame mast so commonly used in tubing operations and in shallow well work.

The device is unusually safe, and exceptionally well guarded. It is specially constructed and so streamlined as to be free from all dangerous projections and hazardous latching arrangements. While there is provided a full-closure housing, it may, nevertheless, be quickly opened to allow immediate and untrammelled reeling and looping of a cable about the sheaves, thus promoting speed and safety and a saving of labor.

The "hook" of the tool is so designed and arranged that it is in effect a compound beam. Two arms carried by the frame of the device receive the load which is apportioned and distributed thereto in amounts of predetermined relation. Such construction presents a "hook" of thinner section and less bulk than usual and one which has even greater load-carrying capacity, despite the apparent paradox.

The advantages of this tool over earlier devices in this art will become apparent as this specification is developed.

Among the objects of this invention are these:

(a) A unitized block and hook, the structure of each supplying some necessary part of the structure of the other, and the two being interrelated in function.

(b) A compact combination of block and hook, so constructed as to be one device having a common frame for load carrying.

(c) A streamlined combination block and hook, which is thinner, narrower and shorter than conventional devices designed to carry comparable loads.

(d) In a combined block and hook, the elimination of the conventional becket and bail; and the saving of material, labor, weight and space over old styled devices.

(e) The combination of a block with a hook in such way as to eliminate pivoting and swinging between these members, and result in a single rigid, straight and compact piece of equipment of greater stability.

(f) The provision of a combination block and

2

hook in which all ordinary and dangerous projections have been eliminated, so that there are no bolts, nuts, ears, dogs, fingers, hooks, or other projections extending beyond the general contour lines of the unitary device.

(g) The provision of a block in which there is a protective housing about the sheaves and removable sheave guards so arranged and carried within the housing as to leave only minimum cable openings into the block, thus promoting safety and preventing the cable from jumping out of the housing or away from the sheaves.

(h) The provision of a combined block and hook having a common rigid frame which may be opened on one side so as to allow a cable to be looped around the sheaves, instead of having to thread a cable into a hole or opening about or around each sheave, as has been the custom. Thus the block may be reeved, without dismantling it, there being no bars across the bottom of the block or below the sheaves.

(i) In a block the provision of an axle for carrying the sheaves, the axle being so arranged that it does not extend through the sheave housing, yet being so constructed as to allow all of the weight carried by such axle to be supported on such housing.

(j) The provision of a hook which is in effect a compound beam, having a plurality of supports, rather than being an ordinary hook of cantilever design.

(k) The provision of a "hook" which is a complete mechanical closure, carrying the weight of the load on two arms or sides of the "hook," rather than on the single arm of the conventional hook.

(l) The provision of the hook so constructed as to function in the manner of a chain link, carrying the load on its two long sides, in contrast with the ordinary single sided hook in which the load tends to deflect and/or rupture the single arm of the hook, because of the leverage afforded to the load by the lateral extension of the lower part of the conventional hook.

(m) The provision of a two-armed hook in which the arms are so related as to afford a V-shaped cradle in which the load may be so carried as to distribute the weight thereof to both arms in predetermined quantities.

(n) The provision of a V-shaped cradle in a hook provided with a rigid arm and a movable arm, both being so arranged that when a load is placed in the cradle the movable arm is kept constantly in such a position as to maintain closure of the hook.

(o) The provision of a hook having two arms

so arranged as to come together to form a cradle for carrying a load, the hook being so constructed that each arm is supported independently of the other.

(p) The provision of a hook in which there is a body extending downwardly and laterally to form a rigid hook, and in which there is a movable arm hung upon a finger extending into the body, such arm likewise extending downwardly and laterally to form a hook.

(q) A hook having two independently supported arms, cooperatively connected, and being capable of supporting greater loads on thinner sections than can be done with the conventional one-armed hook, the latter having to be made thicker and wider and with a greater curve and of greater bulk and weight than is required of the instant device in the carrying of any given load.

(r) The provision of a hook in which the hook body carries a part of the load and in which the hook link carries a part of the load, some of the load carried by the link being transmitted to the body of the hook through the use of a finger inserted therein.

(s) The provision of a hook in which the hook body carries a part of the load and in which the hook link carries a part of the load, some of the load carried by the link being transmitted to the body of the hook through the use of a finger inserted therein, and some further part of such load being transmitted to the body of the hook through the use of a pivot connection between body and link.

(t) The provision of a hook in which the hook body carries a part of the load and in which the hook link carries a part of the load, some of the load carried by the link being transmitted to the body of the hook through the use of a finger inserted therein, and a further part of such load being distributed to the body through the use of a regulating seat carried in the bottom of the hook and arranged to receive some of the weight of the link.

(u) The provision of a hook having a rigid body together with a closing link pivoted thereto, the free end of the link being provided with a downwardly inclined finger by which it may be hung into the upper part of the body, and the finger being so protected by a guard as to prevent its damage or abrasion by any articles being loaded into, carried by or released from the hook.

(v) In a hook with a movable link, a horizontally disposed latch for locking the link in place, thus preventing the unlocking of the hook by any vertically sustained shocks arising from loads being carried by the hook.

(w) The provision of a lateral latch for locking the movable link of the hook, the latch being carried by and operable from the non-dangerous side of the hook, i. e., the side of the hook opposite the movable link, so that no bails, arms, chains or other heavy members may be allowed to fall out upon the operator when he is unlocking the latch.

(x) In a combined block and hook, a swivel bolt arranged therebetween, so as to allow the complete rotation of the hook, and the head of the bolt being so enlarged as to be itself employed as a locking member for directly locking the swivel in any desired position without the necessity of employing an extra or third part or member between a swivel housing and a hook housing for effecting a lock.

(y) Spring actuated plunger means for lock-

ing the hook swivel at any predetermined place on the periphery of the head of the swivel bolt.

(z) The provision of two streamlined side plates arranged to form a housing about a block, and being so constructed that they will come together above the sheaves in complete closure, the side plates being rigidly locked against side thrust by the use of tongued and grooved connections therebetween, and being further united by having a hook rigidly mounted between the lower ends of these plates.

The several advantages of this invention may be incorporated into tools having various sizes, shapes and appearances and employing variants in mechanical construction, because the invention herein is not limited to one particular form. On the other hand, it may be freely practiced in many forms.

In order to best present a suitable form of device employing the essence of this invention, there is provided a series of drawings, in which:

Fig. I is a perspective view of a typical unitized block and hook.

Fig. II is an exploded view in perspective of the device shown in Fig. I, in which the housing is opened, the guards removed, and the hook dropped from one side of the frame.

Fig. III is a partially sectionalized elevation of a typical rigid block and hook, with part of the casing cut away.

Fig. IV is a plan view of the tool shown in Fig. III, when seen from above, with some of the casing cut away.

Fig. V is a cross-sectional elevation taken through the cap of the housing, showing parts of the load-carrying frame therein.

Fig. VI is a sectionalized elevation of a typical hook in compound beam position.

Fig. VII is a strictly schematic diagram intended to indicate the locations of load thrust in this tool.

Fig. VIII is an exploded view in perspective of the swivel collar and its immediately related mechanism.

Fig. IX is a sectionalized view of the swivel locking plunger when engaged.

Fig. X is another sectionalized view of the swivel locking plunger when engaged, with the dotted lines showing position when disengaged.

In the drawings the various parts of this device are represented by numerals, and the numeral 1 indicates a housing, made of two complementary parts, or halves, 1a and 1b. One function of this housing is to cover and protect the sheaves 40, of which there may be several (as desired). It is also intended as a guard to prevent injury to workmen and operators. However, it has another and quite important function.

There are built into the housing certain structural members which are an important part of the load-carrying frame of the entire tool. The chief members of this frame are the posts 22, which may not be seen when the casing of the block is closed. These posts are arranged on the inner faces of the housing 1, so as to receive and support the axle 27, which carries the sheaves 40. The load-carrying skeleton of this device, like that of a turtle, is in its shell.

Posts 22 are made somewhat wider than the diameter of the axle, and they extend upwardly above the axle a short distance. However, each post 22 extends downwardly the full length of the housing, and continues beyond to form the series of smaller posts 2.

Posts **2** may be rigidly (but removably) attached to the rigid collar **60** (itself a part of the frame) through the use of dogs **65** on such collar. These dogs are also plural in number on each side of the collar, and they are arranged to fit nicely into openings between the posts **2**, so that one common bolt **20**, known as the frame bolt, may cause the housing and its inner-frame and the exposed posts to be made up into fixed and rigid connection with the collar **60**.

Also in continuous rigid makeup with the members mentioned immediately next above, there is the special "hook" **100**, which is hung below the collar **60** on the strong spindle bolt **90**. This hook may rotate, but it may not swing. The result is that the entire unitary device, from its extra strong cap **5** down to and through its unusually designed "hook" **100**, is a completely integrated structure presenting a straight and compact tool of great stability.

In thus making a unitized block and hook into one completely integrated tool it is to be observed that the result is a much shorter device than the usual old fashioned and loosely connected assemblage made up of separate block, becket, bail and conventional hook.

In our device the hook and block are made into one complete structure in which certain parts necessary in the block are furnished by the hook and in which certain parts necessary in the hook are furnished by the block.

It is important to observe that all forms of pivots and pivoting usually employed between a conventional block and a conventional hook have been eliminated, and especially is it important to remember that the ordinary becket (usually found below a conventional block) and the ordinary bail (usually found above the conventional hook) are both eliminated because they are altogether useless in the device employing our invention.

The design and construction and arrangement of this device completely prevents the usual and highly undesirable pivoting and swinging and swaying and general uncertainty found in the loosely coupled and non-integrated block and hook used in the past. These old fashioned devices have resulted in the crippling of many men and the damaging of much material and the loss of much property. They are unpredictable in their movements, especially when suddenly freed of loads. Their very looseness favors the accidental loss of loads being carried on the hook; and, even when latched, the swinging hook allows loads to be thrown on the latch and open it. These old devices are particularly dangerous.

Heretofore, some forms of blocks have been made up of a series of flat plates of steel. Plates were usually placed outside of and between each pulley or sheave, so that with several sheaves in a block of that character there was formed a rather bulky assortment of rectangular plates arranged in spaced relation. A loose swinging becket was usually put below these plates and attached to two or more of them. The loose bail of the hook was introduced through the becket and a conventional "one-armed" hook was suspended therebelow. The loosely hung parts of such contrivance represented nothing more nearly than the links in an uncertain chain, any one of which could get out of line instantly, and usually did so.

Now, when great loads were thrown on one side of such a serpentine contrivance (even momentarily) they usually caused a shifting

in the plates. There was lateral thrust, accentuated by leverage. This resulted in a shearing stress upon the axle carrying the pulleys. It also resulted in shearing stress falling upon every bolt and rivet and pin that held the device together. There was frequently no straight or regular up and down pull. On the other hand, there was a lateral or deflecting force felt throughout the block, and especially the plates thereof. They would shift and get loose.

All such troubles have been eliminated in our rigid unitary device which has been provided with an extra-strong internal frame arranged in an unusually narrow casing. To make rigidity and stability more certain and prevent internal stress we have provided machined and matched tongue-and-groove surfaces between the two sides **1a** and **1b** of the housing **1**. This tongue-and-groove arrangement may be disposed wherever convenient between the two members. It has been shown in the drawings herein as tongue **47** and groove **48**; and these members may well take the form of an arc or curve passing entirely across face plates **50** of the reinforced cap **5** of the housing. This stabilizes the housing and prevents any lateral movements between the two halves thereof. There is no shearing movement or lateral thrust within our housing.

Further reinforcement may be added to the members of the housing **1** as desired; and the plates **50** therein may be made to extend outwardly to end in the dogs **6**. These dogs should have faces which will meet perfectly so that the bolts **7** may be passed through the dogs and hold securely together and in perfect alignment the two halves of the housing. Also ribs **51** may be made to run transversely across the cap **5** for further reinforcing.

Still more firmly and rigidly will the housing be held together when the collar **60** is fitted between the halves of the housing and bolted up (with frame bolts **20**).

Transverse ribs **51** may be provided with one or more notches **8**, in which may be inserted teeth **11** of the sheave guard **9**, in order to keep the guard members in perfect alignment with one another and with the housing.

The sheave guards **9** are two in number, and they meet together at the very base of the housing **1** so as to effect complete closure of such housing and to protectively cover and encase the lower part of the sheaves **40**.

The guard **9** continues upwardly and curves about the contour of housing **1** to present a plurality of fingers, of which the outside guard rail **10** is one and the inside guard rail **13** may be one.

Rail **13** may be provided with reinforcing rib **34**, if desired.

The outside rails are provided with flange **12** which not only strengthens the guard, but also helps to seal the housing and keep the guard in perfect fit between the side walls of the housing.

Cable openings **14** are made between the rails of the guard; and these openings are kept to minimum size, being only sufficient to allow the cable to pass therethrough with satisfactory clearance.

Transversely across the lower part of the guard **9** there may be provided a solid reinforcing boss **38**, drilled with hole **17** to receive the guard bolt **45**.

To close the housing, the guard **9** is moved into fitting position over sheaves **40** and within the

side walls of the housing until teeth **11** come within the notches **8** and the holes **17** are lined up with the holes **19**, the latter being provided in the recess **18** of the flange in the housing **1**. The assembly, thus positioned, is held firmly together by the use of bolt **15** and its nut **16**.

Through this construction it will be seen that there has been effected as complete a closure of the housing over the sheaves as is possible. It is impossible for any tools or machinery, or the workmen's hands or fingers to get caught by the sheaves or the cable on either of the flat sides of the block member or the underside thereof. The only openings in the block are in the upper end of the guard, where there are provided the slots **14**. With the block suspended above the work, these openings are up out of ordinary operation range and reach of a workman engaged in attaching parts or tools or chains to the hook **100**, and releasing them therefrom. Safety is an important element of this tool.

It may be desired that this tool be dead-lined to some fixed object, rather than be attached to the top of a mast or pole or derrick. Therefore, the eyelet **4** has been provided through the heavy and strongly reinforced cap **5** of the housing; and above the eyelet **4** there is arranged the ring member **49**, so that a rope or cable passed through this eyelet can be used for safe anchorage, the ring being quite sufficient in strength for this purpose.

The axle **27**, on which are mounted the sheaves **40**, contrary to usual practice, does not extend through the walls of the housing. There are not any dangerous projections, such as bolts and nuts, on the outside of the housing. Such projections might injure a workman or cause the fouling of lines, cables and chains. These very common but objectionable features have been eliminated in our tool.

There have been provided within the frame members **22** a pair of recesses or cups **23** to receive the ends of the axle **27**; and the axle has been reduced in diameter at each end until it assumes the form of diminished ends **29**, which are made to fit into the recesses **23**.

There have been provided axle shoulders **28**, at the points where the axle is reduced in size; and such shoulders rest against the inner faces of posts **22**.

Holes **30** are made through a thin section of the housing **1** so that they will line up with holes **33** which are provided for a certain limited distance into the ends of the axle **27**; and these holes are made to receive axle screws **25**. Usually it is advisable to use two or more such screws on each end of the axle. When these screws are made up, we find that the axle is securely set and held in the cups **23**; yet the heads of machine screws **25** are within the outer contour of the housing **1** by being placed within a recess **24** arranged on the outer face of each wall of the housing. This recess also protects the grease-fitting **26**, which is usually arranged to pass into the center of each end of the axle **27** to facilitate the filling of reservoir **31** with lubricants. A cross channel **32** will allow lubricants from the reservoir to pass outwardly to the periphery of the axle and there lubricate the bearing surfaces.

There should be arranged about the axle, and within the hub **43** of the sheaves **40**, some suitable bearing; and such a bearing may take any one of many forms. In the form indicated in

the drawings the bearing is a roller bearing **35**, of which the rollers are shown as at **36** and the housing as at **37**.

The sheaves themselves may be almost any pulley having flanges as at **41** and a groove as at **42**. A strong yet lightweight sheave may be made to possess ribs **44** on spokes **45** and have spaces **46** cut out between these spokes, if this is desired.

However, most any conventional sheave or pulley may be used in this tool; and one alone may be mounted therein, or two may be used, or several may be used, as the needs and requirements of the job may dictate. Where additional sheaves are added the body of the housing and related gear must be made sufficiently wide to receive them; and appropriate guard members with suitable openings **14** between the rails thereof must be provided. Otherwise, the multi-sheave device will be constructed as generally indicated herein.

It is not at all desired that this tool be allowed to swing or break in the middle (as a link in a chain) for the reason that such breaking is dangerous and unsatisfactory and always results in low efficiency in that it prevents the placement of the tool with any certainty while endeavoring to pick up, raise or lower objects. Such breaking is altogether dangerous.

However, it is quite desirable (notwithstanding the rigid character required of the straight line assembly here presented) that the hook **100** be allowed to rotate freely below the housing of the block section of the device. This is accomplished by the provision of the special swivel collar **60**, which is a part of the rigid framework between the housing **1** and the hook **100**. The hook may be allowed to rotate in this collar whenever desired; and it also may be fixed and locked at most any position desired around the circle of its rotation, all as will be made more plain hereinafter.

Swivel collar **60** is an important element of the structure of this device; and it has several functions. It is a part of the rigid frame of the tool, holding the block member above it and the hook member below it, and keeping them fixedly in line.

Collar **60** is also a part of the base of the block member. It is fitted firmly and exactly into the spaces between the posts **2**, across the bottom of housing, so as to hold together the side members **1a** and **1b** and to give strength to the entire block structure. Bolt holes **3** in posts **2** and bolt holes **66** in dogs **65** are put into alignment to receive the frame bolts **20**, which pass therethrough and are held therein by the use of nuts **21**. The removal of one such frame bolt will allow the collar to drop downwardly, hinged on the other frame bolt. This will open the bottom of the block housing (guards **9** being removed).

Collar **60** has a continuous circular wall **62** therearound, and is provided with the major vertical opening **61** therethrough. The lower part of this opening is so reduced in diameter as to furnish supporting shoulder **63** in the lower part of wall **62** of the swivel collar.

On supporting shoulder **63** there should be arranged a suitable bearing, as at **87**. The one illustrated is a roller bearing, in which **88** indicates the housing and **89** the rollers.

Ball bearings may be used, or any other suitable bearing may be employed. A slight recess **64** may be made within vertical opening **61** (just above shoulder **63**) to receive bearing **87**. This recess is not necessary, but it may be used.

The heavy spindle bolt 90 has a large head 91 and a shank 93, the latter being provided with threads 94. The head of this spindle bolt comes to rest on top of bearing 87, and the shank continues downwardly through the bearing housing and extends below the lower face of swivel collar 60, where it is threaded into hole 102 arranged in the uppermost part of the body of hook unit 100, the hole having threads 103 therein for this purpose.

To firmly fix spindle bolt 90 into the body of hook 100 (after it has been tightly made up with the threaded connection indicated), the hole 104 may be provided through the wall of the body of the hook and into the shank 93 of the spindle bolt; and set screw 105 is then made up into this hole to prevent the bolt from turning in the hook.

With the construction indicated it will be seen that hook 100, firmly attached to spindle bolt 90, is well supported in the framework of collar member 60. The hook may not swing or buckle or break laterally or deviate from the straight center line running through the entire tool, which is always maintained in a fixed alignment of its rigidly structural members.

However, from the construction indicated, it is clear that the hook member 100 will rotate freely in the collar 60. It may be operated in such a manner that it will rotate in response to the weight or tension of any load being carried on the hook. This will allow strains, kinks, twists, torque and thrust within the load being carried (pipe, tubing, rods, chains, cables or any other load) to adjust themselves and find compensation in the free rotation of the hook. Frequently this is an important consideration.

On numerous occasions, and sometimes continuously, it is desirable and even necessary that the hook be fixed and incapable of rotation. Therefore, a locking device is provided for this purpose.

In the past practice some form of extra structure usually has been introduced to hold together the housing of a block and the housing of a hook (they being separate and non-integrated units, loosely assembled). Thus, a third and additional member was used to make connection between the two housings of these separate units. Such a structure is not very satisfactory as a means for braking or locking the hook in non-rotating position. There is too much space required for the extra member, and it adds somewhat to the length of the assembly, and because of this length there is some undesirable leverage given to thrusts arising from normal impulses toward deflection or rotation. The result of which is that a rather bulky member was usually required to span the considerable distance between block and hook and keep them in a position of approximate non-rotation.

In our construction it will be observed that we add no member between housings. In fact, we add no member whatsoever to be locked. We simply drill some holes 92 in the peripheral side walls of the head 91 of the spindle bolt 90. This permits us to lock this spindle bolt firmly, exactly and fixedly at whatever place we desire, so that it cannot rotate.

We may lock the hook in place by the use of so simple a device as a bolt or screw or rod or plunger or knife or finger, which may be made to pass through a hole in the wall of collar 60 and into one of the several holes 92 in the head 91. These latter holes may be as close together as

desired. They may be put in each one-eighth part of the circumference of the head, or in each one-sixteenth, or at any other spacing found suitable.

5. In order to make simple the locking of the spindle bolt 90 and prevent the rotation of the hook 100, a spring-loaded plunger 77 may be arranged to be carried within a protective plunger guard 87 of the side of the collar 60.

10. A plunger hole 75 is made through the side wall of swivel collar 60 to receive plunger 77, and especially the reduced plunger head 78. The hole 75 should be substantially the same size as the holes 92.

15. A plunger keeper 68 may be inserted within recess 74, arranged about hole 75, in the outer wall of collar 60. A couple of holes 73 may be made at the bottom of this recess to line up with holes 74 in the keeper; and screw 72 may be made up in each two of these holes in alignment, until the keeper is firmly fixed into the wall of the collar.

20. The outer face of keeper 68 should be provided with a relatively deep transverse locking groove 69, and a relatively shallow non-engagement groove 70. A plunger passage 76 is provided through the keeper 68, to line up with the plunger passage 75 in the wall of the collar.

25. There is provided a spring well 79 within the body of the plunger 77; and this well continues as an opening through the plunger key 80 and the plunger handle 81. In this well is carried compression spring 82, which is kept in place by spring keeper 83, held securely by screws 86, which pass through screw holes 84 and make up into screw holes 85 in the collar.

30. The handle 81 of the plunger may be provided with notches 99 which will receive any small tool, such as a screwdriver, the handle of pliers or a chisel, or a piece of small pipe. By using such a tool and forcing it downwardly in one of the notches 99, the plunger handle can be rotated slightly. There are only two positions which it may take. It may be in a position in which the key 80 is in locking groove 69; or it may be forced into the other position with the key in the non-engagement groove 70.

35. Because of the differences in the depth of the grooves 69 and 70 it will be found that when the key is in groove 70 the plunger head 78 does not enter hole 92 in the head of the spindle bolt. When the plunger is in this position of non-engagement, the spindle bolt may rotate freely along with the hook suspended on it.

40. 45. However, when the plunger is placed in a position of engagement by having the key 80 down in the deeper groove 69 of the keeper, then the head 78 of the plunger is firmly driven into one of the holes 92 in the head of the spindle bolt, so as to lock the latter and prevent its rotation.

50. 55. The locking device just described is only one of several which may be used for the same purpose. However, this one is very effective, safe, simple and dependable. It is easily mounted on the side of collar 60; and it is so protected that it will always work. It is obvious that different forms of locking devices may be made with the same good operating results, and with safety and dependability.

60. 65. A matter of great importance in this invention is the design, construction and arrangement of the unit known as the "hook," and indicated as at 100. This is no ordinary hook. In fact, it may be more fair to say that it is not a hook at all. If we consider a hook strictly to be a cantilever

11

lever device, then this is not a hook for it does not answer such a definition. The old form, of cantilever design, was called a hook, and properly so. Anything taking the place of it, however much improved, will probably continue to be called a hook in all industrial fields where such devices are used. Therefore, the element 100, in this tool, is herein called a hook solely for convention's sake. Notwithstanding the nomenclature involved, our so-called hook is in effect a compound beam, having support in several places.

The head of the hook body is indicated as at 121; and through this part of the body the spindle bolt 90 is inserted, fixed and carried. The large stock of the head of the body of the hook extends outwardly on both sides of the spindle bolt 90. Its shortest extension forms the laterally disposed fixed arm 122.

The longest arm of the hook is shown as at 101. It is a fixed member extending downwardly from the head 121 and ending in the transverse member which carries the link pin 110.

The third and only remaining arm of this hook is shown as at 112, and it is sometimes referred to as the "link." It is the only movable arm of the hook. When the hook is carrying a load the arm 112 is hung into the short arm 122 through the use of finger 116, which is made a part of the member 112 and allowed to enter the recess 120 in the head of the hook in such manner as to cause the head to support a considerable part of the weight being carried by the arm 112, all as will be more fully explained hereinafter.

A better understanding of the details of construction of the hook member 100 may be had by referring to Fig. VI, in which it will be seen that the fixed arm 101 not only extends downwardly (from the head 121 of the hook), but it also continues as a downwardly and laterally inclined leg 106, which forms one-half of a V-seat in which the load rests.

Beyond member 106 the arm 101 then continues to form the upwardly inclined leg 107, the extreme end of which is provided with hole 109 therethrough to receive link pin 110.

A wide groove 108 bisects the members 106 and 107, so as to receive therein the downwardly inclined leg 113 of link 112, which leg is so arranged as to form one side of the load-receiving V-seat.

Thus, it will be seen that the bifurcated arm 101 receives the lower end of movable arm 112 in the groove or recess 108, and that the link 112 is so pivoted as to move in such groove. Pivot pin 110 is common to both sides of the bifurcated member 107 and also to the lower part of the body of link 112, and may be kept in place by the use of set screw 111.

The innermost end of leg 113 (of link member 112) terminates in the toe 114. This toe may be locked down in such manner as to prevent the movement of the member 112 about the pivot 110. We have indicated a suitable lock 131, which terminates in a latch lip 135; and this lip falls over the toe 114 to lock the link in a position of closure for carrying a load.

An important regulating member 115 is arranged between the toe end (114) of movable link 112, and the transverse base 124 of fixed arm 101. This device is a so-called seat for regulating and distributing load throughout the several load-carrying members of the hook generally.

As indicated in the drawings, one usable form (among several) of the seat member 125 is a screw pin fitted into a threaded hole 126 provided

12

through the base member 124. This form of regulating seat 125 may be screwed up through the hole 126 until its upper face comes in contact with the seat 115 of the link itself. Such adjustment is to be made only when the link 112 is in full load-carrying position, and while a part of this load may be carried upon the finger 116.

It is important to know that there is a very definite relation between the load-carrying member 116 and the adjustable seat 125, which is a load-distributing member.

The adjustable seat 125 should be so arranged and adjusted that it will receive, sustain and carry a certain predetermined amount of the load resting within the V-seat of the hook. (The V-seat is defined by the angles of inclination of the members 106 and 113, when the hook is in load-carrying formation.) Then the adjustable seat may be welded in place by the use of welding 121. Of course, it may be pinned in place. But in any event, once the adjustment for load distribution in predetermined measure or percentage is made, the member 125 should be kept at the desired adjustment. For this purpose suitable fixing means should be employed, whether it be welding or pins or other.

The finger 116 may be inserted in hole 117 made through the free end, or upper end, of link 112. The use of a hole, for adjustably locating finger 116 within link 112, so as to determine the measure of extension therebeyond, is simply a convenient means to facilitate the adjustment to the desired degree of extension; but it is a very satisfactory one. Other means may be used.

Such arrangement as is thus indicated obviously must not preclude the thought and fact that finger 116 may be made originally as an integral part of the free end of link 112; and then such adjustment as is required, in the measure of extension of such finger from the member 112, may be arrived at by machining or otherwise cutting down the exposed end of the finger.

It is important, however, to realize that this finger member should be made the subject of suitable regulation, so that the final arrangement is such that finger 116 will carry and distribute a certain amount of the load (originally laid upon link 112) to the short fixed arm 122, extending from the head 121 of the body of hook 100.

When hole 117 is used as a method of adjusting finger 116, then, whenever the finger is in exactly the right position for load distribution, a bit of welding, as at 118, may be used to permanently unite the finger and the link. (Again a set screw or other pin or means could be used for keeping the finger in permanent location.)

The walls of the hole 120, in the head of the hook, are therefore arranged to carry a considerable amount of the load originally laid upon the link 112. It is to be noted that this hole is nearer to the center line of the hook assembly than is the link pin 110. It is further to be noted that when a weight is laid upon leg 113 it will cause the latter to move downwardly and will also cause the long arm of link 112 to move upwardly and inwardly, in the progress of partial rotation of these members about the link pin 110. Whereupon, the finger enters the hole in the head.

As a result of the movement of the link 112 about pin 110 (when the hook is loaded) there is the distribution of some of the load from link

112 to the head 121, and a further distribution of some of such load to the base 124.

While the adjustable seat 125 may be well employed in the form in which it is disclosed in the drawings, it should be obvious that the same results may be had with a different construction.

For instance, a verticle hole could be made through the leg 113 near the toe 114 thereof. Through this hole a pin, comparable to the member 125, could be inserted and forced downwardly, using threads, until it comes to rest firmly on the upper face of base 124. The result would be exactly the same as with the form indicated in the drawings. Either form of construction may be employed to carry out the principle and effect the objects herein disclosed.

Likewise, it should be obvious that a slight elevation may be made as an integral part of the base 124, the elevation to take the form and contour of the exposed part of pin 125, or not, as desired. Required adjustment could then be made by having the extension machined, or otherwise reduced, until it received exactly the amount of load, or the percentage of load, desired.

Likewise, a projection may be made as an integral part of seat 115 to form a downward extension, until such projection comes into contact with the upper face of 124. Adjustment could be made by machining or filing or otherwise reducing the extent of the projection until the load distribution required was arrived at. When needed, welding could be used to build up any adjusting member found deficient.

In any event, it is proper to remember that there is an adjustable load-distributing member arranged between the seat 115 and the base 124.

Because it is important that the surface of the finger 116 be properly machined and made smooth, and kept that way, it is desirable that there shall be provided a guard 119 about the extended finger.

A simple way to provide this guard is to allow a thin section of each outer wall of both sides of the upper end of link 112 to be continued in the region of the finger 116, to form the walls 119 of a trough in which the finger is located.

It is recommended also that the hole 120 be made perfectly true and accurate and smoothly finished. The finger 116 should fit into the hole 120 and against the walls thereof with perfect nicety. So that this fitting will be gradual and perfect and exact, it is recommended that the end of the finger 116 be tapered, and that the wall of the recess 120 be correspondingly inclined. Thus the finger may be driven into the recess 120 so that it will completely impinge the side walls of such recess. Then the weight carried on the finger will be transferred to these walls. Literally, the link 112 is hung into the body of the hook.

A load thrown into the V-seat of the hook will close the structure. Nevertheless, it is desirable that some form of lock be placed upon this hook so that, when once it is closed and in load-carrying position, it cannot become unlocked accidentally.

It is considered important that the lock be put upon the "safe" side of the hook. The safe side is the side which does not open. It is the side of the fixed arm 101. It is opposite from the movable arm 112 (located on the "dangerous" side of the hook).

Suppose a load were being carried on this hook, and further suppose that the load were set down suddenly. Then the part of the load being carried through the opening of the hook may fly upwardly and outwardly against the link 112, tending to force it open.

If the operator is on the "dangerous" side of the hook, he may be severely injured, or even killed, by the falling material or machinery which comes tumbling out of the accidentally opened hook.

Such accidents and losses are provided against by incorporating in our hook an automatic lock, which is arranged on the "safe" side.

To install lock 131 there should be arranged a protected operating recess 130, in the backside of the arm 101. This recess should continue into a hole 140, extending horizontally through member 101.

Latch body 134 (which well may take the form of a cylindrical or cartridge-like member) is allowed to extend beyond the inner face of member 101, to provide an overhanging lip 135, having a rounded top.

Through both side walls of the tubular member 134 there should be arranged a long horizontal slot 138. Through this slot should be provided pin 139 to extend entirely through the movable member 134, and be fixed in each wall of the arm 101.

The hollow member 134 affords a spring well 136, and in this well is arranged compression spring 137. The spring is disposed between the cross pin 139 and the solid head of the member 134, which solid head is on the end bearing the lip 135. A handle 132 is fixed to the latch body 134, through the use of latch pin 133.

The locking device detailed immediately above allows the handle 132 to be pulled outwardly from the recess 130 in such manner as to entirely withdraw the lip 132 within the body of the arm 101. Then the lock is inoperative; and the arm 112 is unlocked, and the free end of it may be lowered outwardly and downwardly to receive a load.

When a load falls upon leg 113, then the toe 114 is instantly snapped downwardly and under the overhanging lip 135 of the latch 131. Thereafter, and until manually released, the hook is closed and locked; and it cannot be opened by accident.

It is important to note that regardless of the weight thrown upon the load-carrying members of this hook, or the stress created therein, there will be no tendency whatever to unlock our horizontal lock 131. This is to be contrasted with old type vertically disposed latches which yield, or fail, or leave their keepers, when there is a slight elongation on the hook by reason of great weights being carried thereon or because of sudden shifts of such weights.

The position of the foolproof lock which we have presented, on the "safe" side of the hook, is to be contrasted with certain latches which have been put upon the "unsafe" side of a hook, where there is some form of moving link or closing member. The dangerous pins or latches heretofore used have been found on the side of the movable closing member, where tons of machinery may come tumbling down upon a workman and kill him, if he undertakes to open the latch.

The safe and dependable lock disclosed by us herein is further free from being opened accidentally because the handle 132 thereof is kept safely within the recess 130 by the spring 137.

while the lock is engaged. The handle 132 does not extend beyond the outer contour of the body. This is important. No rope, cable, clothing or anything else may catch upon the protected lock handle; and therefore accidental opening of the lock from such causes is entirely eliminated.

Much testing and accurate engineering have gone into the making of this hook of plural members carrying loads. An object of great importance in this invention is predetermined load distribution. The several load-carrying members of this hook are so designed and operated as to share in the load being carried; and the extent of such sharing is determined by the proper use of the hanging finger 116 and the adjusting bridge 125, or their equivalents.

Fixed arm 101 is not a cantilevered device. It is one side of a loaded beam. The member 112 is the other side of that beam. The loads on both members 101 and 112 are hung upon and ultimately carried by the head 121 of the hook. Distribution of the load between the movable arm 112 and the fixed arm 101 is effected by the proper use of suitable means of adjustment, including the bridge between leg 113 and base 124.

The result of such design, arrangement and construction is to minimize the thrust of the load on link pin 110; and to make possible a reduction in the cross-sectional area of each of the load-carrying members themselves.

To put it very succinctly: our hook can carry more weight than any device heretofore known to us as having a single conventional hook of cross-sectional area equal to that of our arm 101. This is so for the simple reason that the full load carried by our hook is not supported by the single arm 101 alone. Much of it is carried by the arm 112. All of it is carried by the head of the hook; and such head is loaded on two opposed sides thereof; and side thrust and leverage against the head is impossible.

It must be made plain that the load carried by movable arm 112 is so carried from the very beginning of the loading of the hook. To put it another way: this device in no wise depends upon the distortion, elongation or deformation of any of its members, in order to transmit some of an overload from one member to another member which theretofore carried no load. It would be a very sorry procedure, indeed, to torture one member, by overloading, until it yielded sufficiently to allow some of the load carried by it to slip to another member which had been carrying no load at all. It is of the very essence of poor design to require the setting up of internal stresses in some one member, in order to cause some other member to function. Yet, that is exactly what has been done in certain earlier hooks. The understanding of this fact is necessary to fully appreciate the design of our hook.

In order that the principle incorporated in the design of our hook may be more easily understood, clearly grasped and graphically illustrated, we have provided a strictly diagrammatic representation of this principle, in our Fig. VII.

In the schematic arrangement of Fig. VII, A represents the fixed arm of the hook, L represents the movable arm of the hook, F represents the load-carrying finger and S represents the adjustable bridge member under compression, which may be thought of as a seat common to members A and L. W represents the weight or load carried.

The small arrows in the diagram show the locations of the load thrust in this tool. For

instance, in the area *a* there is a downward thrust from the finger, counteracted by the resistance of the body or head of the hook.

In the areas *a* and *b*, there is lateral and downward thrust, against the members A and L respectively; and there is corresponding resistance in these members.

Likewise, there is downward thrust in the area *c*, because of the load shifted through the seat or bridge.

There is also a side thrust in the area *d*, toward the link carrying pin, in which there is resistance.

This diagram not only discloses the locations of thrust in the tool, but should make very plain the fact of the distribution of load throughout the tool; and it should also make clear that load distribution can be effected by adjusting the members known as the finger and the seat (or bridge), and especially the latter.

We have presented a very safe block and hook tool of short compass, having a continuous and inflexible frame, a streamlined and projection-free body, an easily opened and freely reeved housing, a rotatable yet easily fixed hook, the latter being provided with plural load-carrying members, adjusting means for distributing load between such members in predetermined measure, and an accident-proof lock, arranged on the safe side of the body.

We claim:

1. In load-supporting oil field hook equipment, a hook head; an arm rigidly depending from such head, such arm having a downwardly and laterally disposed leg which is further extended upwardly and laterally, said leg being bifurcated; a movable link having a downwardly and laterally disposed extension passing into the recess of said bifurcation; a pin carried in the outer end of the bifurcated leg, whereby the link is pivotally mounted; a frusto-conical finger extending laterally from the upper end of the link; a frusto-conical recess arranged in the head to receive the finger; a latch arranged within the arm and provided with a lip extendable into the recess of the bifurcation, whereby the said extension of the link may be releasably secured within such recess; and an adjustable bridge carried in the base of the rigid arm, whereby the said extension of the link may be supportably engaged.

2. In oil field hook equipment, a hook head; a substantially vertically disposed hook arm rigidly depending from said head; a bifurcated lateral extension from said arm, extending first downwardly and then upwardly; a link member pivotally mounted within the bifurcation, such member having a laterally inclined leg provided with an upper face, such face being above and substantially parallel to the upper face of the said upward extension of the arm when the link is closed, and the downward extension of the arm and the inclined leg together forming a V-shaped load-carrying cradle; a finger extending inwardly from the upper end of the link; a recess arranged within the head to receive the finger; an adjustable bridge arranged within the bifurcation to receive the leg of the link when the latter is closed, the adjustment of the bridge permitting weight suspended from the cradle to be adjustably distributed through the finger and through the arm to the head; and link locking means wholly recessed within the rigid arm, such means having a lip extending within the

bifurcation and protected by the side walls thereof.

3. In oil field hook equipment, a hook head, having an opening therein; a substantially vertically disposed hook arm rigidly depending from said head; a bifurcated lateral extension from said arm, extending first downwardly and then upwardly; a link member pivotally mounted within the bifurcation, such member having a laterally inclined leg provided with an upper face, such face being above and substantially parallel to the upper face of the said upward extension of the arm when the link is closed, and the downward extension of the arm and the inclined leg forming a V-shaped load-carrying cradle; a finger extending inwardly from the upper end of the link; a recess arranged within the head to receive the finger; an adjustable bridge arranged within the bifurcation to receive the leg of the link when the latter is closed, the adjustment of the bridge permitting weight suspended from the cradle to be adjustably distributed through the finger and through the arm to the head; link locking means wholly recessed within the rigid arm, such means having a lip extending within the bifurcation and protected by the said walls thereof; a spindle bolt fixedly carried in said opening in the hook head and extending thereabove, such bolt terminating in a bolt head provided with spaced recesses in its peripheral face; a removable collar surrounding the bolt head, whereby it may be rotatably supported; and a releasable latch recessively carried within the collar, the latch being provided with a plunger extendable into any selected recess in the bolt head, whereby the bolt may be locked against rotation.

4. In oil field hook equipment, a hook head, having an opening therein; a substantially vertically disposed hook arm rigidly depending from said head; a bifurcated lateral extension from said arm, extending first downwardly and then upwardly; a link member pivotally mounted within the bifurcation, such member having a laterally inclined leg provided with an upper face, such face being above and substantially parallel to the upper face of the said upward extension of the arm when the link is closed, and the downward extension of the arm and the inclined leg

forming a V-shaped load-carrying cradle; a finger extending inwardly from the upper end of the link; a recess arranged within the head to receive the finger; an adjustable bridge arranged within the bifurcation to receive the leg of the link when the latter is closed, the adjustment of the bridge permitting weight suspended from the cradle to be adjustably distributed through the finger and through the arm to the head; link locking means wholly recessed within the rigid arm, such means having a lip extending within the bifurcation and protected by the said walls thereof; a spindle bolt fixedly carried in said opening in the hook head and extending thereabove, such bolt terminating in a bolt head provided with spaced recesses in its peripheral face; a removable collar surrounding the bolt head, whereby it may be rotatably supported; a releasable latch recessively carried within the collar, the latch being provided with a plunger extendable into any selected recess in the bolt head, whereby the bolt may be locked against rotation; and a thrust bearing supporting the head of the spindle bolt within the collar.
